James H. Taylor

ATTORNEY.

UNITED STATES PATENT OFFICE.

WILLIAM F. FARNSWORTH, OF WASHINGTON, DISTRICT OF COLUMBIA.

NUT-LOCK.

1,400,213.

Specification of Letters Patent. Patented Dec. 13, 1921.

Original application filed November 27, 1920, Serial No. 426,709. Divided and this application filed January 24, 1921. Serial No. 439,711.

To all whom it may concern:

Be it known that I, WILLIAM F. FARNSWORTH, a citizen of the United States, residing at Washington, in the District of Columbia, have invented certain new and useful Improvements in Nut-Locks, of which the following is a specification.

This invention relates to nut locking structures particularly adapted for use in connection with rail joints, and is a division of my co-pending application, Serial No. 426,709, filed Nov. 27, 1920.

An object of the invention is to provide elements held in place by one of the nuts ordinarily employed for tying rails together and in turn engaging a plurality of said nuts to thereby hold all of the nuts against turning.

Further objects of the invention will be set forth in the detailed description which now follows.

In the accompanying drawings:

Figure 1, is a side elevation of a rail joint illustrating the nut locking structure adapted to lock a plurality of nuts against turning;

Fig. 2 as a horizontal section taken on line 2—2 of Fig. 1 and,

Fig. 3 is a perspective assembly of the elements constituting the locking structure.

In the accompanying drawings the numerals 5 and 6 designate the abutting ends of a pair of rails having the usual fish plates 7 overlapping the ends, said fish plates being traversed by bolts 8 and nuts 9 are adapted to bind the same together. In this form of my invention, I employ a group of three bolts, but it is obvious that this number may be increased or decreased.

40 A face plate 19 is provided with an aperture 20 for receiving the end bolt of the group. This face plate has its end turned at a right angle as shown at 21 and is provided with a slot 22, for a purpose to be described.

45 The face plate is offset as shown at 23. The material adjacent the end of the face plate is bent outwardly at 24, upwardly at 25 and inwardly at 26. This forms a boxlike structure for holding a locking bar in place, to be described.

50 The numeral 27 designates a locking bar or strip, having one of its ends reduced as

shown at 28, for insertion in the slot 22. A depending ear 29 is formed on the bar 27, as shown and such ear has a slot 30 formed 55 therein, for engagement with the portion 26. This slot 30 is slightly longer than the part 26, this for the purpose of permitting slight longitudinal movement of the bar 27 with relation to the face plate 19. When in the 60 locked position, the part 26 engages with the fish plate, which position will prevent displacement of the bar 27.

In operation, the face plate is placed over the end bolt and the nut placed thereon and 65 turned down tight. The other nuts are also put on and turned down tight, but all having their sides arranged as shown in Fig. 1. The end 28 of the locking bar is then inserted in the slot 22. A suitable tool is then inserted 70 between the face plate and the fish plate, at a point A, and the plate is sprung outwardly a sufficient distance to allow the insertion of the ear 29 within the space formed by the portion 24, 25 and 26. Removal of the tool 75 allows the face plate to spring back into place, thereby securely holding the bar 27 against displacement. As shown in Fig. 1 the bar 27 rests on the tops of all the nuts in the group to thereby prevent rotation. The 80 reason for making the slot 30 slightly longer than the part 26, is to allow for expansion and contraction of the rails.

It is to be understood that the invention is not limited to the precise construction set 85 forth but that it includes within its purview whatever changes fairly come within either the terms or the spirit of the appended claim.

Having described my invention, what I 90 claim is:

The combination with a nut locking structure adapted to hold a row of the nuts against turning upon their respective bolts comprising a face plate traversed by one of 95 said bolts and held by the nut thereon, a lock bar having an opening formed in a portion thereof, and a projecting element carried by the face plate for engaging in said opening to hold the lock bar in position to engage the 100 sides of a plurality of said nuts.

In testimony whereof I affix my signature.

WILLIAM F. FARNSWORTH.
